(57) **CLAIM**

The ornamental design for a combination charging case and smart ring, as shown and described.

DESCRIPTION

FIG. 1 is a front, left and top perspective view of a smart ring of a combination charging case and smart ring, shown separately to show aspects of the design that are not visible when combined;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, left and top perspective view of a charging case of the combination charging case and smart ring, shown separately to show aspects of the design that are not visible when combined;

FIG. 10 is a rear, right and bottom perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof;

FIG. 16 is a bottom plan view thereof;

FIG. 17 is a front, left and top perspective of the combination charging case and smart ring; and,

FIG. 18 is a front, left and top perspective view of the combination charging case and smart ring, shown in a closed state.

The broken lines shown in the drawings illustrate portions of the combination charging case and smart ring that form no part of the claimed design.
